CARD PUNCH

Charles O. Wellman, Binghamton, N. Y., assignor
to International Business Machines Corpora-
tion, New York, N. Y., a corporation of New
York

Application November 29, 1935, Serial No. 51,990

19 Claims. (Cl. 164—115)

This case relates to card punching machines, particularly to the perforating unit of the automatic, mechanical accounting system, in which record or tabulating cards are perforated in different columns to represent information to be tabulated.

The record card has parallel columns of index point or perforation-receiving positions, in which holes are punched to designate data according to a selected code. For instance, in the Hollerith, single hole code, each character is represented by a single perforation in one index point of a card column. Thus, numbers 1, 2, 3—10, 11, 12 are represented by perforating the corresponding index point positions 1, 2, 3—10, 11, 12 of a card column. These index point positions are progressively distant from a datum line in the order of their magnitude, thereby forming a differential system.

In the type of perforating machine with which this invention is concerned, the card is fed column by column to a single column of punches, which perforate the card columns one after another. The selection of the punches may be made by manual operation of keys or under automatic control of a master or pattern card. The punch selection by the pattern card is for the purpose of duplicating information contained on the pattern card in a plurality of other cards, which, for convenience, may be termed the work cards.

In addition to the information duplicated in the work card, the latter may be punched with additional data, which may be termed individual (card) data. According to the former system of preparing a work card, it is first routed through the machine for an automatic duplicating run, then removed, and subsequently rerouted through a perforating machine for an individual data run.

During the latter run, the card columns not filled in with duplicate data are perforated through manual operation of the keys.

During the duplicating run, the card columns of the work card which are assigned to individual data are usually fed past the punches without accompanying punching operations. This is called the skipping operation and is effected by skipping mechanism.

The skipping mechanism is set in operation under control of a special perforation, usually the X perforation, contained in the pattern card. Ordinarily, the X perforation in the pattern card not only initiates skipping operation but also causes an X hole to be punched in the work card as a preliminary to the skipping operation. In some cases, the X hole in the work card is desirable, as in controlling class selection in tabulating machines, in the manner disclosed in Patent No. 1,976,617. In other cases, it is not

desirable to punch the X hole in a card column, as when the latter is to be used for straight tabulation, without class selection.

Further, if the card with an X hole in a column is used as a pattern card in ordinary duplicating punching machines, then the presence of the X hole will initiate a skipping operation, whereas it may be desired to avoid the skipping in order to duplicate all the data on the pattern card.

Accordingly, an object of the present invention is to provide for selectively perforating or not perforating the first of a series of individual data columns in a work card with a special skip control perforation under control of the pattern card.

A correlative of the latter object is to set the skipping means in operation under an automatic control without reproducing the special perforation in the work card.

Another object is to duplicate a special perforation in the work card, under master card control, without setting the skipping mechanism in operation.

A correlative object is to prevent the special perforation on the pattern card from either initiating skipping operation or being duplicated in the work card.

By attainment of the latter two objects, the card feed may be arrested and the operator may fill in the individual data in the work card through manual operation of the keys. When the individual data has been filled in, the master card may resume its control of the punching and feeding of the work card.

The invention also contemplates the reproducing of the special perforation in a column of the work card together with reproduction of a second, value, perforation in the same column, and to accomplish this result with or without accompanying skipping operation, as may be desired.

Further, the invention contemplates arrest of the card feed under pattern card control and the manually controlled punching of a hole in the work card automatically followed by a skipping operation.

All of above objects, and such others as may appear in the further parts of the specification or be apparent from the drawings, may be considered as embraced in the general object of increasing the flexibility of operation of card perforating machines.

In the drawings:

For purposes of illustration, the invention has been applied to a perforating machine of the type disclosed in Patent No. 1,976,618. Only such parts of the machine will be explained herein 15 as are necessary to an understanding of the present invention.

Referring to Figs. 1 and 4, the pattern card P is moved in the direction of its length along the flat surface of a frame 10 by a pair of gripping and pushing fingers 11 and 12. Finger 12 engages the right hand, lagging edge, of the card to push the card to the left (Figs. 1 and 4) through its active or control stroke while finger 11 engages the left, leading edge of the card to 20 push the card to the right through its inactive, return stroke.

During its movement along surface 10, the pattern card is held down by a pair of cover plates 13 and 14. Plate 13 is fixed in position, 30 while plate 14 is hinged to the frame, at its right end, on pin 15. The left or forward end of plate 14 is latched beneath the nose of a latch 16 urged to the right (Fig. 4) by a spring 17.

Near its rear end, plate 14 journals common 35 contact roll 22 coating with a column of twelve brushes 23 to analyze the perforations of the pattern card. Brushes 23 are spaced correspondingly to the spacing of the twelve index point or perforation positions of a card. To one side 40 of brushes 23, there is an additional, common brush 23'. Card P is fed one step at a time to the left to successively locate the card columns at the analyzing station. When a card column is at 45 analyzing station, a brush 23 reaches through a perforation in the column to engage contact roller 22, and thereby close the following circuit (see Fig. 10):

Duplicating circuit A.—From the + side of the line, through normally closed contacts 24, line 50 25, normally closed contacts 26, floating cam contacts 27 (now closed), common brush 23' of the analyzing station, common contact roller 22, the brush 23 engaging roller 22 through the 55 perforation in card P, the connected duplicating magnet 28, and to the — side of the line.

To disable the pattern card from controlling 60 punching operation, cover plate 14 is raised to separate contact roller 22 from brushes 23, so that duplicating circuits cannot be formed.

Referring to Figs. 1 and 2, work card T rests 65 on a flat surface of frame 10'; its rear, lagging, edge is engaged by a pivoted pusher 29; and its front, leading, edge, is engaged by an abutment 30. Blank cards T are fed one at a time from a 70 magazine 31 into position between elements 29 and 30. Pusher element 29 moves card T to the left to place the card columns in succession at the punching station. The punching station has a column of twelve punches 32 spaced correspondingly to the spacing of the index point positions of a card column, and dies 33 for the punches. When the last column of card T has been punched, the card is removed from the machine.

75 The rear pusher 12 of pattern card P and rear

pusher 29 of work card T are carried, respectively, by transversely extending brackets 34 and 35 fixed to opposite sides of an escapement rack 36 (see Figs. 1, 2, and 3). The front abutments 11 and 30 of cards P and T, respectively, are commonly carried by a bracket 37 secured to the left end of rack 36 (see Figs. 1, 2, 4, and 8). Thus, both cards P and T are compelled to move in unison with rack 36, and brushes 23 and punches 32 are so positioned that like-numbered or corresponding 10 columns of the two cards will be located simultaneously at their respective analyzing and punching stations.

Rigidly secured to but insulated from bracket 34 is a spring metal plate 38, formed with three joined contact fingers or brushes 39, 39', and 39a (see Fig. 1). These fingers being connected to rack 36 through bracket 34, move in unison with cards P and T. Fingers 39 and 39' ride along two rows of contact spots 40 of a stationary 20 column commutator C.

The successive contact spots 40, considering both rows, are spaced apart the width of a card column, and each corresponds to a different 25 numbered card column. The upper row of contacts 40 corresponds to the even numbered card columns and the lower row of contacts 40 to the odd numbered columns. Brush 39 engages the even numbered contacts 40 and brush 39' engages the odd numbered contacts 40. Either 30 brush will be engaging a contact 40 at each column step of advance of rack 36. Brush 39a rides on common contact strip 41 of the commutator. Plug sockets 42, one wired to each contact stud 40 (see Fig. 10, the circuit diagram) 35 are provided in the commutator, so that any column of the commutator may be plugged to a space magnet 45 or a skip magnet 46 (Figs. 3, 7, and 10) wound on opposite poles of a common core 47. The functions of these magnets will be 40 explained later.

Punches 32 may be manually selected for 45 operation by manual depression of value selecting keys 50. In addition to keys 50, the usual space key 50' is provided (see Fig. 1) which, when depressed, effects a step of advance of rack 36 and the cards, without an accompanying punching operation, in a manner known to the art.

Keys 50 may also be automatically depressed under control of magnets 28 energized by 50 previously described duplicating circuits A. The armature lever 52 of each magnet 28 is swiveled to the stem of a separate key 50. When a magnet 28 is energized, it swings its armature lever counterclockwise (Fig. 2) to depress the connected key 50.

Swiveled to the stem of each key 50 is one arm of a bell crank 53, the other arm of which is pivoted to an interposer bar 54. Also connected to each bell crank is a spring 55. When 60 a key 50 is depressed, manually or automatically, it rocks the connected bell crank 53 against resistance of spring 55 to advance the associated interposer bar 54. Each interposer 54 rests at its front end on a different punch 32, and is 65 notched intermediately to provide a vertical shoulder 56 engaged with a common bail 57 fixed to a shaft 58 (see Figs. 2 and 9).

One side 59 of bail 57 carries a horizontally 70 extending pin 59' passing through a hole in the upper end of a vertical link 60. Link 60 extends, intermediately, through an elongated guide hole 61, cut through frame 10'; the sides of the hole prevent lateral movement of the link. The lower end of link 60 is formed with a hook 62 under- 75

lying a spring blade 63 which carries one of the points of a switch 64. In a manner brought out in detail in Patent No. 1,878,930, when any interposer 54 is advanced, its shoulder 56 rocks bail 57 to raise link 60, the hook 62 of which thereupon moves blade 63 upwardly to close switch 64. Closure of switch 64 completes the following circuit (see Fig. 10):

Punch Circuit B.—From the + side of the line, 10 through contacts 24, switch 64, punch magnet 65, and to the - side of the line.

Energization of magnet 65 operates linkage 66 to depress a hammer plate 67 (Fig. 2). The left, forward end of each interposer 54 has a notch 15 54' to freely receive the hammer tip 67' when the interposer is in its rear position.

When an interposer is advanced, the upper edge of the interposer is located beneath hammer tip 67' so that depression of the latter strikes 20 the advanced interposer and depresses it. As a result, the punch 32 beneath the interposer is pushed down by the interposer through card T and into its die 33 to perforate the card in an index point position corresponding to the key 50 25 which has been operated.

Switch 64 is opened by operation of linkage 66 to deenergize magnet 65, and hammer 67 and the depressed punch 32 are restored in a manner fully explained in aforementioned Patent No. 30 1,878,930. When key 50 rises, the advanced interposer 54 returns to the right and its shoulder 56 releases bail 57 which is thereupon restored by a spring 69 (Fig. 2).

Following the punching of a hole in a column 35 of card T, the card is fed one step to place the next column in punching position. Feeding of card T is effected by movement of rack 36, with which pattern card P and feelers 39, 39' and 39a of column commutator C are also movable. For 40 convenience, the rack 36 and the card pushers 11, 12, 29, and 30 connected thereto, may be termed a card carriage. The feeding movement of the card carriage is controlled by escapement mechanism. This escapement mechanism is of 45 the type disclosed in Patent No. 1,426,223, and will be briefly described in order to aid in understanding the present invention.

Below all the interposers 54 is a bail 72 mounted on a shaft 73 (see Figs. 2 and 3). The 50 top of the bail is engaged by all the interposers 54, except the X or "11" position interposer 54—x (see Fig. 7). Thus, depression of any interposer, except the X interposer, will rock bail 72 about its shaft 73. Referring to Figs. 3 and 5, one end of bail 72 is provided with a screw 74 bearing on top of one arm of a lever 75 rotatably mounted on shaft 73. Lever 75 has a pin 76 extending loosely through a hole 77 in escapement pawl 78. The pawl is loosely mounted by 55 means of an elongated slot 78' on shaft 73, in a manner to permit movement of the pawl longitudinally of rack 36. A spring 79 acting on lever 75 holds the latter and bail 72 in counterclockwise position (Fig. 5). Pawl 78 is maintained 60 in engagement with rack 36 by a spring 80 connected to the pawl.

Lever 75 has a screw 81 bearing on part of a member 82 rotatably carried by shaft 73 and urged clockwise (Fig. 5) by a spring 83. Member 82 has a pin and slot connection 84 with a holding dog 85. When in normal, upper, position, bail 72 and lever 75 permit pawl 78 to engage rack 36 and prevent member 82 from moving dog 85 into engagement with the rack.

When punching any value, except the X value,

the advanced interposer 54 is depressed and rocks bail 72 clockwise (Fig. 5). Lever 75 is thereby rocked in the same direction and member 82 follows. As a result, pin 76 raises pawl 78 out of engagement with rack 36 and member 82 lowers dog 85 into engagement with the rack before the rack can advance to the right (Fig. 5). When pawl 78 is raised, its spring 80 moves it to the left to position its nose above the next rack tooth.

After the punching operation, the interposer rises, and bail 72 and lever 75 are returned, counterclockwise (Fig. 5) by spring 79. Pawl 78 is thereupon rocked counterclockwise by spring 80 into the rack tooth above which it had been positioned, while dog 85 is raised by member 82 to release the rack for movement to the right by the usual spring motor (not shown). As the rack moves to the right, it actuates the engaged pawl 78 in the same direction until the pawl 20 is arrested by engagement of the left side of its slot 78' with shaft 73. This limits movement of rack 36 to one step for each reciprocation of bail 12. The step of movement of the rack advances cards P and T and brushes 39, 39', and 25 39a a distance equal to the width of a card column.

To prevent sparking between brushes 23 and contact roller 22 when the pattern card advances, and to time the making of duplicating 30 circuit A, means such as disclosed in Patent No. 1,976,618 are provided for timing the make and break of contacts 27, which are in circuit A. A description of this means follows:

Referring to Figs. 5 and 9; shaft 58, to which 35 bail 57 is fixed, rigidly carries at one end a T-shaped member 87. A floating cam member 88 is rotatably mounted on shaft 58 adjacent member 87. Between the two members is a spring 89 tending to force cam 88 clockwise (Fig. 5). 40 Normally, the side of a finger 88' of cam 88 abuts the side of a transversely extending lug 90 of a pivoted element 91 freely pivoted on shaft 73.

Element 91 has a stud 92 at its free end beneath an insulating block 93 secured to a leaf spring 45 blade 94 which carries one of the points of switch 27 (Fig. 5). The pressure of spring blade 94 is sufficient to hold element 91 depressed with a transversely bent part 96 thereof engaged with the top of escapement pawl 78. In depressed position of element 91, its lug 90 is in front of finger 88' of cam 88 to prevent clockwise rocking of the latter by spring 89.

When a duplicating circuit A is formed, it energizes a magnet 28 to cause advance of an interposer 54, which thereupon rocks bail 57 counterclockwise, as viewed in Fig. 2, and clockwise, as viewed in Fig. 5. Since bail 57 is fast to shaft 58, the latter and the member 87 carried thereby are also rocked clockwise (Fig. 5). As a result, the 60 tension of spring 89 is increased to tend to turn cam 88 more forcibly clockwise, but the cam cannot rock clockwise while its finger 88' still engages tab 90 of element 91. The parts are then in the 65 positions shown in Fig. 5.

Due to the rocking of bail 57, contacts 64 are closed to establish punch circuit B, magnet 65 is energized, and hammer 67 is depressed to effect the punching operation. During the punching operation, bail 72 is rocked clockwise (Fig. 5), resulting in the raising of pawl 78 above and clear of rack 36. When the pawl rises, through its engagement with part 96 of element 91, it elevates the latter so that stud 92 raises spring 75

blade 94 to open switch 27. This occurs during depression of the selected punch 32.

When element 91 is lifted by pawl 78, lug 90 of the element moves above finger 88' of cam member 88, permitting spring 89 to rock member 88 clockwise until another finger 97 of member 88 engages a projection 98 of member 81. With the floating cam member 88 in this clockwise position, the arc of finger 88' is under lug 90 of element 91 and supporting the latter in raised position, thus maintaining switch 27 open after it had been opened by the rise of escapement pawl 78.

When switch 27 opens, duplicating circuit A is broken and the active magnet 28 deenergized, permitting the connected interposer to return. During return of the interposer, bail 57 is restored by spring 69, causing member 87 to rock counterclockwise (Fig. 5) and to similarly rock member 88 through engagement of finger 98 with the then abutting finger 97 of member 88.

Element 91 remains in its raised position and switch 27, therefore, remains open until pawl 78 moves down to reengage rack 36. When punch 25 circuit B is broken by the opening of switch 64, hammer 67 and the depressed interposer 54 rise, permitting bail 72 to rock counterclockwise (Fig. 5). As a result, dog 85 rises to release rack 36 while pawl 78 moves down to arrest the rack and 30 card carriage after the latter have moved one step. This happens while ball 57 is still being restored and while the arc of finger 88' of member 88 is still riding under lug 90 of element 91. When the card carriage has finished its feeding 35 step, then finger 88' rides off lug 90 permitting member 91 to drop and close switch 27.

Thus, switch 27 is held open until both the last-operated interposer is restored and until the card carriage has advanced one step. In this manner, 40 switch 27 is operated to time the making and breaking of duplicating circuits A.

The ordinary operation of the machine to duplicate the data derived from the pattern card on the work card has been explained. A certain field 45 of the work card may be intended for receiving individual data not present on the pattern card. Corresponding to the individual data field of the work card is the skip field of the pattern card. The first column of the skip field has a special 50 perforation in the X or "11" position, and which may hereinafter be referred to as the X perforation.

The present invention provides for duplicating the X perforation in the work card T and arresting the card feed, so as to permit the individual data field to be punched, column by column, through manual operation of keys 50. This will be described under the following heading:

X punching without skipping

60 Fixed to top plate 100 of the machine is an oblong block 101 (see Figs. 1, 2 and 7). Block 101 carries a pivot 102 for a cruciform lever 103 (see also Fig. 9) provided at the outer ends of 65 its horizontal arms with keys 104 and 105. The upper vertical arm of lever 103 has a pair of horizontally spaced apertures 106 and 106', either one at a time to receive the conical tip of a plunger 107 (Fig. 2) slidably mounted in block 101, and urged towards lever 103 by a spring 108 within the block.

70 The lower vertical arm of lever 103 is provided at its free end with a pin 109 which passes through a slot 110 in an ear 111 of bail 57 (see Fig. 9). As explained previously, bail 57 is fixed to its shaft

58. The shaft is slidable, axially, in its fixed journal blocks 112. Near the end of bail 57 which is adjacent the X interposer 54-x, the bail is formed with a vertical notch 113. When key 104 is pressed down, lever 103 is rocked counterclockwise (Fig. 9) and through coaction of pin 109 with slot 110 of bail 57, the bail and its shaft 58 are moved to the right to the position shown in Fig. 9, in which the vertical slot 113 is out of line with the X interposer.

10 When the first column of a skip field of card P reaches analyzing station, the X perforation in this column is sensed by brushes 23. The resulting duplicating circuit A energizes the magnet 28 of X key 50 to advance the interposer 54-x. With 15 bail 57 in the position shown in Fig. 9, when interposer 54-x advances, its edge 56 (see Fig. 2) engages bail 57 to rock it counterclockwise (Fig. 2). This action of bail 57, as previously described, raises link 60 to close switch 64 of punch circuit 20 B. Punch magnet 65 is energized to cause hammer 67 to engage the advanced interposer 54-x, and through the latter to depress the punch 32 for perforating the X position of the first column 25 of the individual data field of card T.

It has been stated before that all the interposers 54 except the X interposer are engaged with the top of bail 72 to rock the latter during the punching operation. Reciprocation of bail 72, it will be remembered, causes the feeding 30 mechanism to feed the cards one step to bring their next columns to operating positions. As indicated in Fig. 7, bail 72 is formed with a recess 114 below interposer 54-x. Consequently, upon depression of interposer 54-x during punching 35 of an X hole in card T, this interposer moves down into recess 114 without disturbing bail 72. Since bail 72 is not affected by depression of interposer 54-x, the bail does not cause operation of escapement pawl 78 (Fig. 5) to release 40 rack 36. Thus, pawl 78 constitutes means, operable under the prescribed conditions, to prevent card feeding operation upon the punching of an X hole.

When there is no pattern card P in the machine or when the pattern card is rendered ineffective by raising cover plate 14 (Fig. 4) and the common contact roll 22 carried thereby, then the X hole may be punched in card T by manually depressing the X key 50, but as before, the card 50 carriage will not advance.

The condition now is that the first column of the individual field of card T has been perforated in the X position under control of the X hole in the first column of the skip field of card P, and 55 that the card carriage has remained at rest, so that the first columns of the individual field and the skip field are still at their respective punching and analyzing stations.

The operator may now manually depress keys 60 50 to punch the individual field of card T, column by column, with the desired individual data. If the first individual data column is to bear only the X hole, already punched, then space key 50' is operated to cause the card carriage to 65 advance one step, bringing the second columns of the individual field and of the skip field to their respective operating stations.

The machine is also capable of punching an additional value in the X-punched card column. 70 When the X hole in card P was analyzed, the duplicating circuit advanced the X interposer, punching operation resulted, and the cards remained at rest. Since escapement pawl 78 has not been raised, floating cam contacts 27 re- 75

mained closed, and consequently the X-duplicating circuit A remained in force to hold the X interposer in advanced position. Ordinarily, only one interposer at a time can be advanced 5 due to the usual pivoted interlocks 115 at the rear ends of the interposers (see Fig. 6). To permit an additional hole to be punched in the X-punched column, the X interlock element 115 is removed, so that any other interposer may be 10 advanced although the X interposer is still in advanced position.

Thus, when the card feed has been stopped as an incident to an X punching operation, the operator may depress a key 50 for selecting a 15 value other than X to be punched in the X-punched column. The punching of the additional, selected, value is followed by the usual escapement operation to feed the card carriage one column step.

20 If the skip field of card P is blank except for the X perforation in the first of its columns, then there will be no duplicating circuits formed while the columns of the skip field following the first column are passing through the analyzing station. Accordingly, the operator, without interference from the duplicating section, may punch the second, third, et seq., columns of the individual data field under manual control by depressing the desired character keys 50. Each time, a key 30 50 is operated, the selected value will be punched in an individual data column, and the cards fed one step. Thus, the individual data field will be perforated column by column with data selected by manual operation of keys 50. When the last 35 of the individual data columns has been punched, the accompanying feed step will locate the first column of card P following the skip field at the analyzing station. The perforation in this duplicating column will be analyzed, forming a duplicating circuit to cause punching in the first column of card T following the individual data field. Thus, the duplicating operations under pattern, 40 card control may be resumed automatically after the individual data field has been punched under 45 manual control.

If the skip field of card P instead of being blank in the columns following the first one, has 50 perforations in these columns, and it is not desired to duplicate these perforations in card T, then while the card carriage is at rest following 55 punching of the X hole in card T, the operator raises cover plate 14.

This removes common contact roller 22 of the 55 analyzing means from cooperating relation with brushes 23, so that the analyzing mechanism is disabled to prevent formation of duplicating circuits. The individual data may then be perforated without interference from the pattern card mechanism. After punching the last 60 individual data column, the operator may replace cover plate 14 in operative position, and automatic duplicating and feeding operations under control of card P will be resumed.

65 If the skip field of card P has perforations in the columns following the first one, and it is desired to duplicate these perforations in the individual data field of card T, then when the card feed is interrupted following the punching 70 of the X hole in card T, the operator depresses space key 50'. This brings the second column of the skip field to analyzing station, and automatic duplication under control of card P is continued.

If in the case just described, it is desired to 75 perforate the first individual data column with

another value in addition to the X hole, then instead of depressing the space key, the necessary value key is operated, after which automatic duplication of the perforations in the rest of the skip field follows.

If the first column of the skip field of card P has, in addition to the X perforation, still another perforation, then the X hole and the other hole will both be duplicated in the work card. The duplication of the X hole will not cause skipping 10 or feeding of the card, but the simultaneous duplication of the other perforation will cause the card carriage to advance one column step.

Suppression of X duplication

Referring to Fig. 9, when it is desired to suppress X duplication, the operator depresses key 105. This rocks lever 103 clockwise, placing aperture 106' in front of plunger 107 which thereupon locks the lever in its clockwise position. When 20 lever 103 is rocked clockwise, its pin 109 coacts with slot 110 of bail 57 to move the bail to the left, thereby alining notch 113 with interposer 54—x and edge 56 of this interposer. Now, when 25 an X duplicating circuit is formed, the X interposer advances and passes freely through notch 113 of bail 57. Consequently, bail 57 is not disturbed, link 60 is not lifted, switch 64 is not closed, punch circuit B is not established, and punch magnet 65 is not energized. Thus, the X hole is 30 not punched although the X interposer has been advanced. Further, the card feeding mechanism has not operated, and the cards, therefore, remain in the same column positions.

With this condition, manual depression of space 35 key 50' or of a value key 50 would cause formation of a punch circuit B, which would cause depression of hammer 67. Since the X-duplicating circuit A is still in force and consequently the X-interposer 54 still in advanced position, depression 40 of hammer 67 would depress not only the advanced space key interposer or the advanced value key interposer, but would also necessarily depress the advanced X interposer, thus causing an X punching in card T, which would defeat the 45 object of suppressing X duplication. Accordingly, before depressing the space key or a value key 50 (other than the X key), the X-duplicating circuit A must be broken to cause retraction of the X interposer. Circuits A have, in common, switch 50 26, and it is by opening this switch that the duplicating circuits may be opened at will.

The means for opening switch 26 at will will now be explained.

Referring to Figs. 1 and 2, at the left end of 55 the machine, there is a thumb piece 120 (see also Fig. 8), which is part of a horizontal lever 121, pivotally mounted, by a stud 122, on bracket 37 which is fixed to rack 36 and carries pushers 11 and 30 of cards P and T, respectively. The end 60 of lever 121 opposite the thumb piece 120 is formed with a rearwardly and then downwardly bent tail 123 which engages the cross bar 124 of a bail carried by a shaft 125 journaled in the frame. The rod 124 extends lengthwise of the 65 machine (see Fig. 3) so as to be engaged by tail 123 in any column position of the card carriage.

A light spring 126 connected at one end to lever 121 and at the opposite end to a pin 127 fixed to bracket 37 normally holds lever 121 at its 70 clockwise limit (as viewed in Fig. 1) determined by engagement of the back of lever 121 with a tab 128 bent upwardly from bracket 37. By pressing on thumb piece 120, the operator may rock lever 121, about pivot 122, counterclockwise 75

(as viewed in Fig. 1) until the front of the lever abuts pin 127. As lever 121 rocks counterclockwise, its depending tail 123 presses on rod 124 to rock shaft 125 clockwise (Fig. 8). Extending 5 downwardly from shaft 125 is a rigid arm 130, the lower end of which is in front of a spring blade 131 carrying one of the points of switch 26, the companion point of which is on a blade 133. Switch 26 is normally closed. When shaft 125 is 10 rocked clockwise, its arm 130 engages spring blade 131 and displaces it to the left (Fig. 8), thereby separating the points of switch 26 to open the X-duplicating circuit A. As a result, the X magnet 28 is deenergized, and the X interposer 54 15 is retracted.

Now, while pressing on thumb piece 128 to maintain it in its counterclockwise position (Fig. 1), so that switch 26, and thereby, the X-duplicating circuit, remains open, the operator, at the 20 same time, depresses either space key 50' or a value key 50. If the space key is depressed, the card carriage merely is advanced one column step, whereas if the value key is depressed, the punching 25 of the manually selected value precedes the column advance of the card carriage. The operator may then continue to perforate the successive columns of the individual data field with the manually selected values.

In above manner, the presence of an X hole 30 in the pattern card P, when ball 57 has its notch 113 in line with interposer 54—x causes arrest of the card feed, while at the same time, the X duplication is suppressed. Thus, the individual field of card T may be perforated in all its columns with the manually selected individual data, 35 unaccompanied by an X duplication in the first individual data column.

Skipping without X punching

40 It has formerly been necessary to punch an X hole in order to initiate skipping operation. If the punching operation was proceeding under pattern card control, then it was necessary to have an X hole in the first column of the skip 45 field of the pattern card to initiate skipping operation. The present invention provides for means to skip any desired field of a card without requiring X punching or control by an X duplicating circuit.

50 The instant skipping mechanism also makes use of the ordinary skip bar 140 (Figs. 1, 2, 3, 5, and 7), removably attached to rack 36, and having depressions 141 in its upper edge to provide high and low portions. The spacing of these portions 55 and the length of each portion is dependent on the particular requirements of the punching job. If it is desired, for example, to permit skipping of the twenty-fifth to thirty-sixth card columns, then the skip bar is provided with a high portion 60 of corresponding length and arranged along a corresponding part of the travel of rack 36. This skip bar construction and its purpose are disclosed in detail in Patent No. 1,426,223.

As in the previous machines, skip bar 140 coacts 65 with a skip lifter 142. This skip lifter extends transversely of the skip bar, is constrained to move transversely of the skip bar, and is normally in retracted position with its reduced right end 142' (as viewed in Fig. 7) located directly above 70 the skip bar and underneath escapement pawl 78 (see also Fig. 5). The skip lifter is mounted at its rear end on a pin 143 (see Fig. 3) which also provides a pivotal connection between a pair of toggle elements 144 and 145. Element 144 is 75 pivoted to the frame on a stud 146, and element

145 is connected to a leaf spring 147. These two elements constitute a toggle, held to either side of dead center or neutral position by a spring 147. Pivoted element 144 is formed with oppositely and laterally extending ears 148 and 149. Ear 5 148 is in front of and normally at a distance from a vertical, depending projection 150 of bail 72.

Thus far, the old parts of the present skip mechanism have been described. The new parts of the skip mechanism, peculiar to the present 10 invention will now be described.

Engaged with the front of ear 148 of element 144 is a pin 152 extending upwardly from the forward end of arm 153a of a bell crank lever 153 journaled on the lower end of a vertically 15 extending, fixed, pivot 154. The other arm 153b of bell crank lever 153 extends in front of previously mentioned skip magnet 46. Journaled on the upper end of pivot 154 is an arm 156 parallel to arm 153b. The two arms 153b and 20 156 are rigidly joined to each other by a vertically disposed armature plate 157.

Magnet 46, when energized, attracts armature plate 157 to rock bell crank lever 153 clockwise (Fig. 3). As lever 153 rocks clockwise, its pin 25 152 presses against ear 148 of element 144 to rock the latter counterclockwise. This movement of element 144 actuates skip lifter 142 forwardly, (to the right, as viewed in Fig. 7), and the skip lifter is thereafter held in this position 30 due to the shifting of the toggle, comprising elements 144 and 145, to the opposite side of neutral from that shown in Fig. 3.

When skip lifter 142 is moved forwardly, the inclined shoulder 142a (Fig. 7), between the narrow end 142' and the body of the lifter, rides up onto the top of skip bar 140 until the part of the lifter behind the shoulder 142a is resting on top of the skip bar. The skip lifter is thus elevated by the skip bar. If the skip lifter rode up on a high portion of the skip bar, then the narrowed end 142' of the skip lifter was raised sufficiently high to engage escapement pawl 78 and lift the pawl clear of rack 36.

If the skip lifter rode up on a low portion 41 45 of the skip bar, it was not raised high enough to release pawl 78 from rack 36.

When the skip lifter rides up on a high portion of the skip bar, pawl 78 is released from rack 36 and the card carriage is released for 50 continuous feeding operation, during which the selected card columns of cards P and T skip past their respective operating stations.

The skipping operation is initiated by energization of skip magnet 46. When it is desired 55 to skip the individual data field of card T and the corresponding skip field of card P, magnet 46 should be energized when the first columns of these fields arrive at their operating stations. For this purpose, the operator runs a plug wire 60 160 from plug socket 161 in circuit with magnet 46 (see Fig. 10), to that plug socket 42 of commutator C (see also Fig. 1) which corresponds to the first column of the fields to be skipped. Thus, if the twenty-fifth card column is the first 65 column to be skipped, then wire 160 is plugged to the socket 42 connected to the twenty-fifth contact spot 40 from the right, as viewed in Fig. 1. Plug wire 160 connects the selected socket 42 to plug socket 161 which is at the end of line 162 70 running through skip magnet 46.

It will be recalled that brushes 39, 39' and 39a are attached, through bracket 34, to rack 36 to move in unison with the cards, that brush 39 75 wipes the upper row of contacts 40 which cor- 75

respond to even numbered columns, and that brush 39' wipes the second row of contacts 40 which correspond to odd numbered columns. When any card column is at its operating station, then the brushes 39, 39', and 39a are in corresponding column position along commutator C.

Thus, if the twenty-fifth card column is at operating station, then brush 39' is engaging the twenty-fifth contact 40 of the commutator. Now 10 if the latter contact 40 is wired to skip magnet 46, the following circuit will form (see Fig. 10):

Skp circuit C.—From the + side of the line, through normally closed contacts 24, line 25, contacts 26, floating cam contacts 27, line 162, skip 15 magnet 46, plug socket 161, plug wire 160, plug socket 42, the twenty-fifth column contact stud 40, brush 39', brush 39a, common strip 41, and to the - side of the line.

Energization of magnet 46 initiates operation 20 of the skipping mechanism, as explained above, resulting in continuous feeding of selected columns of cards P and T past their respective analyzing and punching stations.

The number of columns skipped is determined 25 by the length of the high portion of skip bar 140 onto which the skip lifter 142 has been elevated by the action of magnet 46. When the skip lifter was elevated, it raised pawl 78 to release rack 36. As long as the skip lifter remains on 30 a high part of the skip bar, it continues to hold pawl 78 in rack release position. When a depression 141 of the skip bar reaches the skip lifter, the latter drops, permitting pawl 78 to move down and reengage rack 36, thus stopping 35 the skip feed.

When pawl 78 was raised by skip lifter 142 to effect the skipping operation, the pawl rocked member 91 clockwise (see Fig. 5). As a result, pin 92 of member 91 lifted spring blade 94 to 40 open floating cam contacts 27 which are common to duplicating circuits A. Accordingly, during the skip feed, switch 27 is continuously open to prevent making of the duplicating circuits under control of any perforations which may be 45 present in the skip field of the pattern card.

The first skip column of card P usually has an X perforation. When this column reaches analyzing station, a duplicating circuit is formed through the X magnet 28. If, as has been 50 promised here, the contact stud 40 corresponding to the first columns of the skip and individual data fields has been plugged to magnet 46, then, at the same time as a brush 23 engages common contact roller 22 to form the X duplicating circuit, brush 39 or 39' has engaged a contact 40 to form circuit C for energizing the skip magnet 46. Thus, the circuit through the skip magnet is completed at the same time as the circuit through the X magnet 28. The skipping mechanism, accordingly, is placed in operation by 55 energization of magnet 46 while the X interposer is being advanced by X magnet 28. Before advance of the X interposer can proceed far enough to cause a punching operation (by rocking bail 57 to close switch 64), the skip lifter has been moved onto the high portion of skip bar 40. The skip lifter has thereby been elevated to lift escapement pawl 78 which in turn, through member 91, opened switch 27 to break the X duplicating circuit A. Consequently, X magnet 28 is deenergized and the X interposer stops advancing and is retracted. Thus, when the duplicating and skipping circuits are simultaneously formed, switch 27 is opened before the interposer advanced by the duplicating circuit can cause punch

circuit B to make. This result is made even more certain by reason of skip magnet 46 being designed to act more quickly than magnet 28.

Circuit C of magnet 46 is also through switch 27 which, as described above, is opened by operation of the skipping mechanism. Hence, circuit C is broken at the same time as the circuit A through the duplicating magnet 28. But due to the toggle action of elements 144, 145, and 147, the skip lifter remains in advanced position after 10 circuit C has opened to deenergize magnet 46.

As explained before, the skip feed continues until a low portion 141 of the skip bar arrives beneath the skip lifter. As a result, the latter drops, pawl 78 reengages rack 36, and switch 27 15 closes. At this time, the first columns of cards P and T following the skipped fields are at operating positions. The duplicating operations are then resumed in the manner already described. The first of the latter duplicating operations causes energization of a magnet 28 to 20 advance the connected interposer 54. When the latter advances, it rocks bail 72 counterclockwise (Fig. 2) causing the depending finger 150 thereon (see Figs. 3 and 7) to press against ear 149 25 of toggle element 144 for returning the toggle to its initial position, shown in Fig. 3. This results in the retraction of the skip lifter. Thus, the first numerical punching following the skip feed completes restoration of the skipping mechanism.

When punching a card solely through manual depression of keys 50, the duplicating parts being rendered inoperative by lifting of cover plate 14 or being omitted altogether, the same skipping 35 mechanism may be used to effect skipping without punching an X hole in the first skip column.

Further, if desired, this may be done independently of control by the column commutator or skip magnet 46. For this purpose, a finger 40 button 165 (see Figs. 1, 3, and 7) is fastened to armature plate 157 of magnet 46. By pressing on button 165, the operator rocks lever 153 clockwise (Fig. 3) to initiate skipping operation in the same manner as though magnet 46 were energized. 45

Automatic spacing with X punching

In prior art machines, the X perforation in the pattern card initiates skipping operation. If 50 card T being punched in the instant machine is to be subsequently used as a pattern card in a machine of prior type, then it must now be punched with an X hole in the first of the columns to be skipped. The X hole in a column is 55 also employed in tabulating machines to control class selection, as disclosed in Patent No. 1,976,617. For these reasons, it may be desired to skip columns of card T accompanied by the usual X punching in the first of the columns to be skipped. 60 The present invention accordingly provides means to effect skipping with an accompanying X punching.

To punch an X hole in the work card, and automatically feed the card one column step, bail 57 65 is first adjusted to its right hand position, shown in Fig. 9, in which notch 113 is out of line with the X interposer. When the column of card P containing the X hole comes to analyzing position, the X interposer is advanced and rocks bail 70 71, causing link 60 to rise, close switch 64, and form punch circuit B to energize punch magnet 65. The punch magnet then operates linkage 66 to cause hammer plate 67 to effect an X punching.

As explained previously, the X interposer, when depressed by the punching operation, does not rock escapement control bail 72, and therefore, the card feed is ordinarily interrupted following the X punching. If, instead of interrupting the card feed, it is desired to automatically feed the card only one column step following the X punching, then plug socket 42 of the column commutator contact 40 which corresponds to the first column of the skip field of card P, is connected by plug wire 166 to one of the plural plug sockets 167 at the end of line 168 passing through the previously mentioned space magnet 45. At one end of line 168 is a switch 169 which, when in full line position (Fig. 10) places magnet 45 in series with a pair of normally open contacts 170. The latter contacts are closed when punch-operating linkage 66 is actuated to depress hammer plate 67 (see also Fig. 2). Under the prescribed conditions, commutator contact 40 corresponding to the first column of the skip field of card P and to the first column of the individual data field of card T has been plugged to space magnet 45. Now, at the same time as the latter card columns reach their respective operating stations, the contact 40 corresponding to these columns is engaged by a brush 39 or 39'. The first result is that a duplicating circuit A is formed under control of the X hole in the first column of the skip field of card P. This circuit A energizes X magnet 28 to advance the X interposer. Since bail 57 has been placed, as promised, with its notch 113 out of line with the X interposer, the advance of the latter rocks the ball to cause link 60 to close switch 64, thereby forming punch circuit B. The latter circuit energizes magnet 65 to operate linkage 66 for depressing hammer 67 to cause the X punch 32 to perforate the X position of the first individual data column of card T.

When linkage 66 depresses hammer 67 to effect X punching, the linkage also closes contacts 170. As a result, the following circuit is formed (see Fig. 10):

45 Space circuit D.—From the + side of the line, through contacts 170, switch 169, line 168, space magnet 45, a plug socket 167, a plug wire 166, a plug socket 42, the connected contact 40 which corresponds to the X-punched card column, brush 39 or 39' one of which is now engaging the latter contact 40, brush 39a, strip 41, and to the - side of the line.

The above circuit energizes magnet 45 to attract its armature 172.

55 Armature 172 of space magnet 45 (see Figs. 3 and 7) is rigid with a bell crank lever 173 journaled on a fixed, vertical pivot 174. Arm 173a of lever 173 extends in front of bail 72, and its free end passes through a notch 175 in a member 176 rotatably carried by shaft 13 of the bail (see Figs. 2, 3, and 7). Member 176 lies within a plane passing between a pair of interposers 54, and is narrow enough not to be disturbed by depression of these interposers. The upper part of member 176 abuts the cross bar of bail 72.

When magnet 45 is energized, it rocks lever 173 counterclockwise (Fig. 3) and arm 173a moves to the left (Fig. 2) thereby actuating member 176 counterclockwise. Member 176, in turn, rocks bail 72 in the same direction. The latter thereupon causes pawl 78 to release rack 36 and dog 85 to engage the rack. This is the same action as when any advanced interposer 54, except the X interposer, is depressed by hammer 67.

75 During the punching operation, switch 64 is

opened to deenergize the punch magnet and linkage 66 is restored; consequently, contacts 170 open. Opening of contacts 170 breaks circuit D, of space magnet 45; bail 72 rises, restoring lever 173, raising dog 85, and lowering pawl 78 into engagement with rack 36. The card carriage thereupon feeds one column step, advancing cards P and T and brushes 39, 39', and 39a the distance of one column width, in the manner previously explained. Thus, the X hole has been punched, and the cards have been fed one column step to place their next columns at operating positions.

Automatic spacing without X-punching

15

It may be desired to space the cards along, column-by-column, without causing an X duplication. Further, it may be desired to space the cards along, step-by-step, independently of any punching operation.

20

As explained previously, to suppress X-punching, key 105 (Fig. 9) is depressed to move bail 57 to the left, where its notch 113 is in line with the X interposer. In addition to placing the bail 57 in its leftward position, the commutator contact 40 corresponding to the first skip column, containing an X hole, is plugged, as before, to space magnet 45. Further, switch 169 (see Fig. 10) is placed in dotted line position, to connect the space magnet and floating cam switch 27 in series.

25

Now, upon arrival of the first skip column of card P at analyzing station, a circuit A is formed through the X hole in this column, the X interposer is advanced, but due to its registering with notch 113 of bail 57, the latter is not disturbed, and switch 64 of punch circuit B remains open. Consequently, no punching operation occurs.

30

At the same time as duplicating circuit A is formed, contact 40 corresponding to the first skip column is engaged by a brush 39 or 39', as a result of which the following circuit is formed:

35

Space circuit D'—From the + side of the line, through contacts 24, switch 26, floating cam contacts 27, switch 169 (now in dotted line position), line 168, space magnet 45, plug wire 166, contact 40, brush 39 or 39', brush 39a, strip 41, and to the - side of the line.

40

Circuit D' energizes magnet 45, which through the previously described, mechanism effects a column advance of the card carriage, during which, incidentally, escapement pawl 78 rises to open switch 27 of the X duplicating circuit A.

45

In the absence of a pattern card P or when the pattern card is rendered ineffective, the same circuit D' may be formed under control of commutator C to cause an automatic column advance of the card carriage.

50

It may be desired to space the entire skip field and individual fields of cards P and T, respectively, past their operating stations, not only without an X duplication, but further, without regard to skipping mechanism or to the skip bar 140. The spacing mechanism is adapted to feed several columns of the card T or cards T and P past the operating stations, independently of punching or duplicating operations, and without using the skip mechanism. For this purpose, the successive column commutator contacts 40 which correspond to the columns to be spaced past the operating station are each individually plugged to space magnet 45.

55

Since the X hole in the first skip column is not to be duplicated, bail 57 is adjusted to its left hand position (Fig. 9) and the circuit of the

70

75

space magnet is made through floating cam switch 27, as in the case just described. When the first, X-punched, skip column of card P reaches analyzing station, circuit D' is formed in the manner already described, and space magnet is energized to cause rocking of bail 72 for effecting a step of advance of the cards and of brushes 38, 38', and 39a. Brush 38 or 38' thereupon engages the next contact 40 plugged to magnet 45 and the latter repeats its operation. Thus, the cards may be fed step by step without accompanying punching and without regard to the absence or presence of a skip bar 140 and to the contour of the latter.

X Punching with skipping

It may be desired to punch an X position in the first of the individual data columns of a card T and to skip the remaining individual data columns. It has already been explained that the space magnet 45 may be energized by circuit D under control of commutator C and through punch armature contacts 170 to automatically effect a single column spacing of the card carriage as an incident to an X-punching operation. When it is desired to punch an X hole in a column of card T and then rapidly skip a succeeding number of card columns past the operating station, the contact 40 corresponding to the column to be X-punched is plugged to space magnet 45. The next column contact 40 is plugged to skip magnet 46. In addition, bail 51 is placed with notch 113 out of register with the X interposer, and switch 169 is set in full line position (Fig. 10).

Now, when the first skip column of card P, containing an X hole, reaches the analyzing station, circuit A forms, advancing the X interposer which rocks bail 51 to cause contacts 64 to close and form punch circuit B. Linkage 66 thereupon operates to depress hammer 67 for effecting X punching in the first individual data column. Linkage 66 also closes contacts 170 of space circuit D and since the contact 40 corresponding to the first skip column has been plugged into circuit D, the latter circuit is completed during the X duplicating operation. As a result, space magnet 45 is energized to operate the escapement mechanism for causing a column advance of the card carriage, incidentally opening switch 27 to break the X duplicating circuit, all as previously described. The second columns of the skip and individual data columns are now in operating positions and either brush 39 or 39' is now engaging the corresponding contact 40 which has been plugged to the skip magnet 46. As soon as brush 39 or 39' engages the latter contact 40, skip circuit C forms causing energization of magnet 46 to advance skip lifter 142 and under control of skip bar 140 to effect rapid skipping operation, in the manner previously described.

Thus, the first individual data column may be punched with an X hole under control of pattern card P (or by manual depression of a key 50) and by plugging successive contacts 40 to the space and skip magnets 45 and 46, in that order, a desired number of following card columns may be skipped past the operating station.

Summary

Assume a pattern card P to have a skip field containing columns 7 to 15, of which column 7 has an X hole and of which columns 8 to 15 are blank. Further, assume column 16 of card P to have a perforation.

First.—Suppose that it is desired to duplicate the X hole in column 7 of a work card T and arrest card feed.

Bail 51 is first adjusted to the position shown in Fig. 9 where notch 113 and X interposer 54—x 5 are out of line.

When column 7 of card P reaches brushes 28 and contact roller 22, a circuit A is formed to energize X magnet 28 which causes the X interposer to advance. During this advance, the X 10 interposer rocks bail 51 to lift link 60 which closes contacts 64. Closure of contacts 64 forms punch circuit B which energizes magnet 65 to operate linkage 66 for depressing hammer plate 67. Tip 67' of the hammer plate strikes the advanced X 15 interposer to effect punching by the X punch 32 of an X hole in column 7 of card T.

The X interposer during its depression by hammer 67 moves into recess 114 of escapement operating bail 72. The latter therefore remains 20 at rest and escapement pawl 78 continues to maintain the card carriage in column 7 position.

Now the operator may depress space key 50' to move columns 8 of cards P and T to their operating station or may depress a value key (other 25 than the X key) to punch an additional hole in column 7 of card, followed by an escapement operation which brings columns 8 of cards P and T to operating station. Columns 8 to 15 of card T may then be punched by successive manual 30 operation of keys 50. After the last such punch operation, the cards are in column 16 position. Here card P contains a perforation and duplicating operations automatically resume.

The above briefly summarizes X punching without skipping.

Second.—Suppose it is desired to X punch column 7 and skip columns 8 to 15. Column 7 contact spot 40 of commutator C is plugged to space magnet 45 and column 8 contact spot 40 is plugged 40 to skip magnet 46. Further, switch 169 (Fig. 10) is placed in full line position to route the circuit of the space magnet through punch armature contacts 170. Bail 51 is left in the position shown in Fig. 9.

As before, when column 7 of card P reaches analyzing station, X magnet 28 is energized to cause X punching in column 7 of card T. During the X punching, linkage 66 closes contacts 170. Since the card carriage is in column 7 position, 50 brush 38' is engaging the contact spot 40 plugged to space magnet 45, and when contacts 170 close, circuit D forms to energize the space magnet. Energization of the latter operates arm 173a (Fig. 2) to the left to rock bail 72 downwardly to effect 55 an escapement step. The card carriage is then in column 8 position where brush 39 engages the contact 40 plugged to skip magnet 46. This forms circuit C to energize magnet 46. Magnet 46 thereupon advances skip lifter 142. Skip bar 140 has 60 a high portion extending from column positions 8 through 15 and when skip lifter 142 rides up on this high portion, the card carriage is released for rapid, continuous travel to column 16 position. Here, skip bar 140 has a depression 141 and 65 skip lifter 142 drops to terminate skipping operation.

In above manner, X punching and skipping may be effected.

Third.—If it is desired merely to duplicate the 70 X hole in column 7 of card T and space to column 8, then as in the second case, column 7 contact spot 40 is plugged to space magnet 45 and the latter connected through switch 169 to contacts 170 which are closed by punch operation. Un- 75

like the second case, the contact spot 40 corresponding to column 8 is not plugged to skip magnet 46. Hence, the card feed will be arrested after the card carriage is moved to column 8 position under control of space magnet 45. Manually selected punching operations may then be effected in columns 8 to 15 of card T.

Fourth.—If it is desired to suppress duplication of the X hole and arrest card feed, ball 57 is moved to the left to register its notch 113 with the X interposer. When column 7 of card P is analyzed, X magnet 28 is again energized to advance the X interposer. The latter moves through notch 113 without actuating ball 57 so that link 68 is not raised to close contacts 64 of punch circuit B. Then by pressing on button 120, contacts 26 in the circuit of X magnet 28 are opened, the magnet is deenergized and the X interposer retracted. While pressing on button 120, the space key 58' or a value key (other than the X key) will be operated to advance the cards to column 8 position. Columns 8 through 15 may then be punched under manual control.

Fifth.—If it is desired to skip columns 7 to 15 by a rapid, continuous feeding movement, without any punching operations, column 7 contact spot 40 is plugged to skip magnet 46. When the card carriage reaches column 7 position, circuit C of the skip magnet will be completed and skipping operation will be effected under control of a high part of skip bar 140 extending from column 7 position through column 15 position.

Sixth.—If it is desired to skip columns 7 through 15, without punching operations, by a less rapid, step-by-step or intermittent feeding movement, and without regard to a skip bar, the contact spots 40 corresponding to columns 7 through 15 are each plugged to space magnet 45. Further, switch 169 is placed in dotted line position (Fig. 10). Now, when the card carriage reaches column 7 position, circuit D' will form to energize magnet 45 which will cause the card carriage to move to column 8 position. There, circuit D' will again form, and a second column advance will occur. Thus, the card carriage will be stepped along column by column through column positions 7 to 15.

It is understood that there may be variations and combinations of the six cases explained above.

Further, it is understood that variations, modifications, and changes in the form of the illustrated embodiment may be made without departing from the spirit or scope of the invention. I therefore wish to be limited only by the following claims.

What is claimed is as follows:

1. In a machine for punching a card having columns of index point positions; the combination of punches for punching one card column at a time, selecting mechanism for causing the punches to perforate selected index point positions of the card columns, means for automatically following the punching operation by a card feeding operation, and means effective upon the punching of a special perforation in a card column under control of the selecting mechanism for automatically interrupting card feeding operation to thereby arrest the latter card column in punching position for receiving an additional perforation.

2. In a machine for punching a card having columns of index point positions; the combination of punches for punching one card column at a time, automatic selecting mechanism for caus-

ing the punches to perforate selected index point positions of the card columns, means for automatically following the punching operation of a card column by a column step feeding operation, and means effective upon the punching in a card column of a special perforation selected by the automatic selecting mechanism for automatically interrupting card feeding operation to thereby arrest the latter column in punching position to receive an additional perforation.

3. In a machine for punching columns of a work card; the combination of punches for perforating the card columns one at a time, automatic selecting mechanism for selecting the punches for operation, means for automatically following selection and operation of a punch by a card feeding operation, and means controlled by the automatic selecting mechanism when it selects a predetermined punch for a certain card column for automatically interrupting card feeding operation to arrest the latter card column in punching position.

4. In a machine for punching columns of a work card under control of perforations in a pattern card; the combination of punches for perforating the work card column by column, mechanism controlled by the pattern card for selecting the punches for operation, means for automatically following selection and operation of a punch by a card feeding operation, and means controlled by a special perforation of the pattern card for automatically interrupting the card feeding operation.

5. In a machine for punching columns of a work card under control of perforations in a pattern card; the combination of punches for punching the work card column by column, mechanism controlled by the pattern card for selecting the punches for operation, means for automatically feeding the work card one column step following selection and operation of a punch, and means effective upon the operation of a punch under control of a special pattern card perforation for interrupting card feeding operation.

6. In a machine for punching work card columns under control of perforations in a pattern card; the combination of punches for perforating the work card one column at a time, mechanism controlled by the pattern card for selecting the punches for operation, means for automatically feeding the work card one column step after each punching operation, means effective upon the selection of a special punch by the pattern card for interrupting card feeding operation, and means thereupon operable to cancel the selection of the special punch.

7. In a machine for punching work card columns under control of perforations in a pattern card; the combination of punches for perforating the work card one column at a time, mechanism controlled by the pattern card for selecting the punches for operation, means for automatically following a punching operation by a work card feeding operation, means effective upon the selection of a special punch by the selecting mechanism for interrupting card feeding operation, and means also capable, upon the selection of the special punch, of suppressing operation of the latter punch.

8. In a machine for punching columns of a record card; the combination of punches for perforating the card columns, mechanism for selecting the punches for operation, means following a punch selection for effecting punching operation

by a selected punch, and a device having alternative positions, in one of which it suppresses the operation of a selected punch by aforesaid means and in the other of which it renders the aforesaid means effective to operate the selected punch.

9. In a machine for punching columns of a record card; the combination of punches for perforating the card columns, mechanism for selecting the punches for operation, means operation of which is initiated by the punch selecting operation for causing the selected punch to perforate the card, and a device adjustable to a position for suppressing initiation of operation of aforesaid means by the punch selecting operation.

10. In a machine for punching columns of a record card; the combination of punches for perforating the card columns, mechanism for selecting the punches for operation, means for operating the selected punches to perforate the card, a device operated by the punch selecting mechanism for initiating operation of aforesaid means, and means for rendering said device ineffective for operation by the punch selecting mechanism whereby operation of the punch operating means is suppressed.

11. In a machine for punching columns of a record card; the combination of punches for perforating the card columns, punch selecting mechanism including an element actuated to effect punch selection, a device moved by the element upon actuation of the latter, means rendered effective by the device upon movement of the latter by said element for operating the selected punch to perforate the card, and means for disabling the device from movement by said element to thereby prevent the device from causing the punch operating means to operate the punch selected by said element.

12. In a machine for punching columns of a record card; the combination of punches for perforating the card columns, punch selecting mechanism including an interposer advanced to effect selection of a punch, a device in the path of advance of the interposer to be moved by the latter, means rendered effective by movement of the device by said interposer to operate the selected punch for perforating the card, and means for displacing the device from the path of advance of said interposer to prevent the latter from moving the device whereby the punch operating means fails to operate the punch selected by said interposer.

13. In a machine for punching a card; the combination of punches, punch operating means to cause the punches to perforate the card, punch selecting means including an interposer advanced to effect a punch selecting operation, a pivoted bail actuated by the advance of the interposer for initiating operation of the punch operating means, and means for shifting the bail in the direction of its pivotal axis, the bail having a notch brought into register with the interposer upon the aforesaid shifting of the bail and through which the interposer freely advances without actuating the bail whereby the bail may be rendered ineffective to initiate operation of the punch operating means to operate the punch selected by said interposer.

14. The machine as defined in claim 13, said bail shifting means including a pair of finger keys, one of which is operable to position the bail with its notch in register with the advancing interposer and the other of which is operable to set

the bail with its notch displaced from the path of advance of the interposer to cause advance of the latter to actuate the bail.

15. In a machine for punching columns of a record sheet; the combination of punches for perforating the sheet one column at a time, means for selecting the punches for operation, punch operating means for causing operation of the selected punches, means for feeding the sheet past the punches, a magnet, a circuit controlled by the punch operating means for energizing the magnet as an incident to a punching operation, and means operated by energization of the magnet for causing the feeding means to feed the sheet a single column step.

16. In a machine for punching columns of a record sheet; the combination of punches for perforating the sheet column after column, means for selecting the punches for operation, punch operating means for causing the selected punches to perforate the sheet, mechanism for feeding the sheet past the punches, and means apart from and independent of the punch selecting means for causing the feeding mechanism to continuously feed a plurality of selected columns of the sheet past the punches without accompanying punching operation.

17. In a machine for punching columns of a record sheet; the combination of punches for perforating the sheet column after column, means for selecting the punches for operation, punch operating means for causing the selected punches to perforate the sheet, mechanism for feeding the sheet past the punches, skipping mechanism for causing the feeding mechanism to continuously feed a plurality of columns of the sheet past the punches, and a device apart from and independent of the punch selecting or operating means for initiating operation of the skipping mechanism when a selected column of the sheet reaches the punches.

18. In a machine for punching columns of a record sheet; the combination of punches for perforating the sheet column by column, means for selecting the punches for operation, punch operating means for causing the selected punches to perforate the sheet, mechanism for feeding the sheet past the punches, skipping mechanism including a skip bar, a skip lifter coacting with said skip bar to release the feeding mechanism for continuous operation, and a device apart from and independent of the punch selecting means for causing the skip lifter to coact with the bar for effecting release of the feeding mechanism when a predetermined column of the sheet reaches the punches.

19. In a machine for punching columns of index point positions of a card; the combination of punches including a special punch for perforating a special index point of the card, means for selecting the punches for operation, mechanism for feeding the card, punch operating means for causing the selected punches to perforate the card, a device actuated under control of the selecting means for causing the feeding mechanism to feed the card one column step after operation of any of said punches except the special punch, and means apart from the punch selecting means capable of automatically operating said device to cause the feeding mechanism to automatically feed the card one column step following operation of the special punch.

CHARLES O. WELLMAN.
